DESIGN FOR A GLOVE

Hilda Woller-Duff, New York, N. Y.

Application September 6, 1946, Serial No. 133,093

Term of patent 3½ years

(Cl. D3—11)

To all whom it may concern:

Be it known that I, Hilda Woller-Duff, a citizen of the United States, residing at New York, in the county of New York and State of New York, have invented a new, original, and ornamental Design for a Glove, of which the following is a specification, reference being had to the accompanying drawing, forming a part thereof.

In the drawing:

Fig. 1 is a front view of a glove showing my new design, and

Fig. 2 is a rear view thereof.

I claim:

The ornamental design for a glove, as shown.

HILDA WOLLER-DUFF.
